O. BOLDIN

COLLAPSIBLE CHAIR

Filed Oct. 8, 1923

UNITED STATES PATENT OFFICE.

OTTO BOLDIN, OF NEW YORK, N. Y.

COLLAPSIBLE CHAIR.

Application filed October 8, 1923. Serial No. 667,101.

To all whom it may concern:

Be it known that I, OTTO BOLDIN, a citizen of Germany, residing at New York, in the county of New York and State of New York, have invented certain new and useful Improvements in Collapsible Chairs, of which the following is a specification.

This invention relates to collapsible chairs, tables, benches or the like, and it has for a general object to provide a novel device of this kind characterized by simplicity of construction, a further object relating to the provision of means for extending or contracting the device in length.

For further comprehension of the invention, and of the objects and advantages thereof reference will be had to the following description and accompanying drawing, and to the appended claims in which the various novel features of the invention are more particularly set forth.

Fig. 1 of the drawing is a front elevation view showing one embodiment of my improved device.

Fig. 2 is an underside plan view thereof.

Fig. 3 is a perspective view showing a different embodiment.

Fig. 4 is a fragmentary plan view of the device shown in Fig. 3.

Fig. 5 is a side view of the central longitudinal seat bar.

Fig. 6 is a transverse section taken on the line 6-6 of Fig. 5.

Referring now to Figs. 1 and 2 of the drawing, in which I have embodied my invention in a stool, or backless chair, the chair top or seat is indicated generally at 10 and is of skeleton construction and comprises a number of longitudinal bars 10' united at their ends by the crosspieces 11. These crosspieces 11 extend across, and are secured to the under sides of the bars 10' and thereby form stops or abutments for the legs 12 of the stool, when such legs are extended to vertical position.

The legs 12 are arranged in two pairs, the respective legs of each pair being united by the rigid crosspieces 14 which serve to hold them securely connected together. These legs are hinged as at 15 to the chair top, the hinge axes being above the crosspieces 11, as clearly shown in Fig. 1. The legs 12 are maintained in vertical position by means of the pairs of struts 17 each of these struts being formed by a rod which

is arranged midway between its ends to form a partially closed loop 18, the two halves of the rod diverging away from one another and being formed with outturned ends 19 which pivotally engage the respective pairs of legs at points substantially midway between the tops and bottoms of the latter. To hold these struts in the operative position shown a short longitudinal rib 22 is formed on the underside of the top and is formed with a pair of upwardly entering transverse slots or notches 23 in which the loops 18 of the struts 17 are adapted to be engaged. Pivoted to this rib 22 is a double ended locking bar 25 which is adapted to engage under the said loops 18 to hold them in the notches 23, this bar being turned to the side when the legs are to be collapsed. When the device is collapsed the legs are swung to positions between the side ones of the bars 10' and the next adjacent ones, and as clearly shown in Fig. 2 of the drawing, the legs at one end have a less spacing from one another than the legs at the other end so as to fold within the confines of the latter. The seat may be provided with a back element 28 which I have shown as hinged thereto, and which may be provided with suitable means such as lugs 29 engaging the seat top, to hold it erect.

In Figs. 3 to 6 I have shown my invention applied to a seat which is extensible in length so as to accommodate one or two persons as may be desired. The top is made up of a number of bars each comprising two sections 30 and 31. The sections 30 are bifurcated as at 30' while the sections 31 are adapted to engage in the bifurcations of the sections 30. Fixed to the sides of these sections 31 are metal straps 32 which prevent lateral displacement of the other sections. Formed in the overlapping portions of the respective bar sections of the central one of the seat bars are longitudinal slots 35 and 36 through which is passed a headed bolt 37. Surrounding this bolt, below the seat bar is a cam element 39 which is engaged by a second cam element 40 also surrounding the bolt and fixed to a locking bar 50 which is swingably mounted on the lower end of the bolt. The upper portion of the bolt, or that extending through the slotted seat elements and the cam 39 may be square to prevent turning of the bolt and of the cam.

Fixed to the underside of the respective sections of the said central bar are a pair of blocks 52, 52', these blocks having transverse notches 43 on their undersides to receive the struts 17 which are pivoted to leg elements 12' corresponding to the leg elements 12, and thereby hold the said legs extended vertically. The locking bar 50 is of sufficient length to engage these blocks when 10 the seat is extended to its full length. It will be noted that when the locking bar is extended longitudinally to engage the blocks 52, 52' the cams 39 and 40 are in a relative position to clamp the overlapping seat section elements together and so lock the seat in the position to which it may have been adjusted, the blocks 52, 52' in this position forming an abutment against which the pull of the bolt 37 is transmitted through 20 the bar 50. To facilitate the bar riding over the blocks to position thereon it may be beveled on the top face as indicated at 54. To brace the bottom one of the bar sections 30' the straps 32 may have attached 25 thereto metal plates such as 56 which extend under the bars. The locking bar 50 is made up of a central section to which are hinged, as indicated at 60 in Fig. 5, the end elements 50', sliding bolts such as 62 being applied in a well known manner to the centre and end members to keep the latter extended. When the seat is contracted these 30 end elements are swung laterally beside the centre element.

35 I have here shown the seat as provided with a back comprising the end arms 59 hinged to the seat and united by telescopic bars each comprising two sections 60, 61

which may engage each other similarly to the sections 30, 31.

Having thus described my invention what I claim as new and desire to protect by Letters Patent of the United States is as follows:

A device of the class described comprising a seat element formed of a number of longitudinal bars, said bars being each formed of two sections slidably overlapping one another at adjacent ends, the overlapping ends of one of said bars being formed with registering longitudinal slots, legs hinged to the ends of the seat and adapted to be swung to collapsed position between said bars, a rib on the underside of the seat element formed with a pair of notches on its underside, a pair of struts hinged at one end to said legs and adapted to engage in said notches at their opposite ends to hold the legs in extended position, a locking bar pivoted to said rib between its ends and adapted to engage under the said notches to hold the said struts engaged therein, a headed bolt passing through the said slots to which the said locking bar is pivoted, a cam surrounding said bolt below the said overlapping seat bar sections and being movable longitudinally on the bolt but held against displacement therefrom, and a second cam fixed to the said locking bar and also surrounding the said bolt and adapted to be engaged with the first cam to clamp the two sections of the seat bar together when the locking bar is swung to operative position.

In testimony whereof OTTO BOLDIN affixes his signature.

OTTO BOLDIN.
